(57) **CLAIM**

The ornamental design for a device for extracting and amplifying nucleic acid, as shown and described.

DESCRIPTION

FIG. 1 is a top front right side perspective view of a device for extracting and amplifying nucleic acid, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top front perspective view thereof showing one door in an open position;

FIG. 9 is a top front perspective view thereof showing one drawer in an open position;

FIG. 10 is a top front perspective view thereof showing another door in an open position; and,

FIG. 11 is a top front perspective view thereof showing two doors and one drawer in an open position.

The broken lines depict portions of the device for extracting and amplifying nucleic acid that form no part of the claimed design.
